CONTENTS ELEVATOR FOR CONTAINERS

Llewellyn Biggs, Leonia, N. J.

Application August 10, 1940, Serial No. 352,151

3 Claims. (Cl. 206—41.1)

My invention relates, generally, to elevators for the contents of containers and in particular to the improvement of such elevators in tape form associated with deep containers such as pocket-size tobacco boxes.

An object of the invention is to provide such an elevator tape attachment for raising the unused portion of tobacco to a convenient level for removal of the contents by the consumer.

Another object of this invention is to provide means for engagement between the tape and the container body whereby the tape may be held in a position at which it supports the contents at a desired elevation.

Still another object is to provide the tape with a permanently tacky adhesive as the means for maintaining it in a contents-elevating position so that the adhering end of the tape may be readily removed from one elevating position and reattached at another position on a container wall.

Yet another object of the invention is the provision of a transparent elevator tape of this character so that lithographed or printed matter on the container wall may not be hidden by the tape.

Many other objects and advantages of the invention will be apparent as it is better understood from the following description, which, taken in connection with the accompanying drawings, discloses a preferred embodiment thereof.

Referring to the drawing:

Fig. 1 is a perspective view of an open hinge-cover, pocket-size, tobacco container in which a preferred form of my invention is embodied.

Fig. 2 is an enlarged longitudinal section taken substantially along the line 2—2 in Fig. 1 but with the cover in closed position.

Fig. 3 is a modified form of the tape shown removed from a container, but in the shape it would assume if in the container.

Fig. 4 illustrates another modification.

Fig. 5 shows a modification of Fig. 4.

Convenience of access to the contents of a container is of prime importance to the consumer and must, therefore, be at least equally important to the manufacturer and vendor who are interested in the sale of such containers and their contents. Probably the best illustration of such convenience to the consumer is by way of a pocket-size tobacco box and for this reason I have chosen it wherewith to show the novelty and usefulness of my invention. In the ordinary package of this type, the consumer finds increasing difficulty of access to the contents as tobacco is removed for use. This is so because the level

gradually recedes from the effective reach of a finger into the box.

I am aware of many attempts to solve this problem but do not believe that any prior device is as satisfactory from the point of view of the manufacturer or consumer as is my present invention which is quite inexpensive, highly efficient and extremely simple in operation.

Throughout the following detailed description of my invention, the same numerals or letters will be used to designate like figures or parts.

Referring to the drawing, the reference numeral 11 designates the deep container, a pocket-size tobacco box, having a cover 12 hinged at 13 to the body of the box, and enclosing a paper envelope or bag 14 which contains the granulated tobacco or other dispensable material. The elevator tape for raising the bag is designated generally by the numeral 15 and comprises, principally, an envelope- or bag-engaging end 16 and a box-engaging end 17 with an intervening strip portion 18 which passes upwardly from end 16 between the outer wall of bag 14 and an inner wall of box 11, and thence outwardly of the box to unite with end 17. As shown in Figs. 1 and 2, end 16 is fixed to the lower end of the envelope 14 and end 11 engages the outer surface 19 of a front wall of the box 11.

The tape may comprise a strip of paper, Cellophane, or other flexible and preferably transparent material attached at end 16 on its obverse side to the envelope or on its reverse side to an inner wall of the box, as shown in dotted lines at 20 in Fig. 2, to form a sling for the bag; by an adhesive 21 or other suitable means, and having, on the reverse side of the tape, an adhesive coated surface 22 at the end 11 adapted to engage the surface 19 of the box 11 either permanently or temporarily depending upon the nature of the adhesive. However, I prefer to use an adhesive on both ends which is permanently tacky, such as a rubber latex, compounded with resin and a suitable plasticizer, which adhesive is well known in the art.

At the extremity 23 of the tape end 17 I provide a finger-hold which may be an uncoated portion on the box-engaging side such as at 25 in Fig. 4, or, as shown in Figs. 1, 2, 3 and 5, a small tab 26, of paper or the like, may be placed over a short length of the adhesive coating at that extremity, a free portion, 27, of the tab being allowed to extend beyond the end of the tape proper. Such a finger-hold enables the consumer to grasp and remove easily the end 17 from the box surface prior to each use of the elevator tape.

With the tab between his fingers, and the box cover in raised position, the operator may pull the tape to raise the tobacco in the envelope 14 to a desired level and then reapply the adhesive-coated surface 22 at the end 17 to a lower position on the surface 19 of the box. A slight pressure upon the end of the tape will secure it with sufficient tenacity to support the tobacco envelope at its new elevation, such as that shown at 28 in dotted lines in Fig. 2. The excess top portion of the bag may then be torn away or folded inwardly, and the container closed again.

Fig. 3 shows a modified form of the elevator tape. In this instance, the construction of the elevator tape 15 varies from that shown in Figs. 1 and 2 only in that it is built up from two strips, an upper length 30 and a lower length 31, each coated throughout on one side with permanently tacky adhesive 32 and placed in overlapping relation so that the adhesive surfaces are in contact over a considerable portion of their lengths. In this construction I still provide an envelope-engaging adhesive surface 21 and an adhesive box-engaging surface 22 at the end 17 which is also provided with a finger-hold tab 26. One advantage in this construction is the ease with which it may be made from the continuously coated cellulose strip material now in common use and sometimes sold under the trade name of "Scotch" tape. Another advantage lies in the doubling of the plies along that portion of the elevator tape which passes over the edge 33 of the mouth of the box, (see Figs. 1 and 2). The extra ply provides added protection against tearing along this edge.

Figs. 4 and 5 show a single-ply tape 35 coated throughout its length with an adhesive 32 on one side only. An obvious advantage in this construction is that it may be made from less of the same material used in the construction shown in Fig. 3. However, these continuous one-ply constructions require modification of the end 17 to provide a box-engaging adhesive surface 22 such as shown in the Figs. 4 and 5. In Fig. 4 the end 17 terminates in a fold 36 which divides the tape length into a short arm 37 and a long arm 38. Adjacent fold 36, the long arm 38 is provided with an aperture 39. The imperforate short arm 37 is reversely folded, back over the apertured portion so that a limited area of the adhesive surface of the imperforate short arm 37 may be projected through the aperture 39 and pressed against the surface 19 of the box to serve as a box-engaging surface 22 as in the previously described constructions. I might add that I do not intend to limit the length of the imperforate short arm 37 to that shown in full lines in Fig. 4, but may carry it back over the adhesive surface 32 of the under layer to a point within the box 11 such as at 41, and thereby attain the advantage of a double ply over the edge 33 of the mouth of the box, similar to the construction shown in Fig. 3.

Fig. 5 shows the single-ply tape of Fig. 4 with the end 17 folded over at right angles and upon itself to provide a laterally extending portion 42 which engages the box surface 18 along an adhesive surface 22 to which is attached a finger-hold tab 26.

It is thought that the invention and many of its attendant advantages will be understood from the foregoing description, and it will be apparent that various changes may be made in the form, construction and arrangement of the parts without departing from the spirit and

scope of the invention or sacrificing all of its material advantages, the form hereinbefore described being merely a preferred embodiment thereof.

I claim:

5. A contents elevator comprising a lower and an upper length of tape overlapped for a portion of their lengths and attached to each other within said overlapping lengths, a lower length projecting section beyond one end of said overlapping portion, an upper length projecting section beyond the other end of said overlapping portion and a permanently tacky adhesive coating on one side of said upper length projecting section, said elevator being adapted to be used with a deep container having an opening, and a contents-holding bag within said container, said lower length projecting section being attached to a lower portion of said bag, said overlapping portion extending upwardly from said attachment to said bag, between contiguous areas of said container and said bag, thence outwardly over an edge of said container opening and downwardly over the outer surface of said container, said adhesive coating on said upper length projecting section being removably attached to said container outer surface, whereby the elevation within said container of said bag may be varied.
10. A contents elevator comprising a lower and an upper length of tape, each coated on one side with a permanently tacky adhesive and overlapped for a portion of their lengths, adhesive sides in contact, and thereby attached to each other throughout said overlapped portion,
15. a lower length projecting section beyond one end of said overlapping portion presenting an obverse adhesive-coated side of said tape, and an upper length projecting section beyond the other end of said overlapping portion presenting a reverse, adhesive-coated side of said tape, said elevator being adaptable to be used with a deep container having an opening, and a contents-holding bag within said container, said lower length projecting section being attached by means of said obverse adhesive coating to a lower portion of said bag, said overlapping portion extending upwardly from said attachment to said bag, between contiguous areas of said container and said bag, thence outwardly over an edge of said container opening and downwardly over the outer surface of said container, said reverse adhesive coating on said upper length projecting section being removably attached to said container outer surface, whereby the elevation within said container of said bag may be varied.
20. A contents elevator comprising a lower and an upper length of tape, each coated on one side with a permanently tacky adhesive and overlapped for a portion of their lengths, adhesive sides in contact, and thereby attached to each other throughout said overlapped portion,
25. a lower length projecting section beyond one end of said overlapping portion presenting an obverse adhesive-coated side of said tape, and an upper length projecting section beyond the other end of said overlapping portion presenting a reverse, adhesive-coated side of said tape, said elevator being adaptable to be used with a deep container having an opening, and a contents-holding bag within said container, said lower length projecting section being attached by means of said obverse adhesive coating to a lower portion of said bag, said overlapping portion extending upwardly from said attachment to said bag, between contiguous areas of said container and said bag, thence outwardly over an edge of said container opening and downwardly over the outer surface of said container, said reverse adhesive coating on said upper length projecting section being removably attached to said container outer surface, whereby the elevation within said container of said bag may be varied.
30. A contents elevator comprising a lower and an upper length of tape, each coated on one side with a permanently tacky adhesive and overlapped for a portion of their lengths, adhesive sides in contact, and thereby attached to each other throughout said overlapped portion,
35. a lower length projecting section beyond one end of said overlapping portion presenting an obverse adhesive-coated side of said tape, and an upper length projecting section beyond the other end of said overlapping portion presenting a reverse, adhesive-coated side of said tape, said elevator being adaptable to be used with a deep container having an opening, and a contents-holding bag within said container, said lower length projecting section being attached by means of said obverse adhesive coating to a lower portion of said bag, said overlapping portion extending upwardly from said attachment to said bag, between contiguous areas of said container and said bag, thence outwardly over an edge of said container opening and downwardly over the outer surface of said container, said reverse adhesive coating on said upper length projecting section being removably attached to said container outer surface, whereby the elevation within said container of said bag may be varied.
40. A contents elevator comprising a lower and an upper length of tape, each coated on one side with a permanently tacky adhesive and overlapped for a portion of their lengths, adhesive sides in contact, and thereby attached to each other throughout said overlapped portion,
45. a lower length projecting section beyond one end of said overlapping portion presenting an obverse adhesive-coated side of said tape, and an upper length projecting section beyond the other end of said overlapping portion presenting a reverse, adhesive-coated side of said tape, said elevator being adaptable to be used with a deep container having an opening, and a contents-holding bag within said container, said lower length projecting section being attached by means of said obverse adhesive coating to a lower portion of said bag, said overlapping portion extending upwardly from said attachment to said bag, between contiguous areas of said container and said bag, thence outwardly over an edge of said container opening and downwardly over the outer surface of said container, said reverse adhesive coating on said upper length projecting section being removably attached to said container outer surface, whereby the elevation within said container of said bag may be varied.
50. A contents elevator comprising a lower and an upper length of tape, each coated on one side with a permanently tacky adhesive and overlapped for a portion of their lengths, adhesive sides in contact, and thereby attached to each other throughout said overlapped portion,
55. a lower length projecting section beyond one end of said overlapping portion presenting an obverse adhesive-coated side of said tape, and an upper length projecting section beyond the other end of said overlapping portion presenting a reverse, adhesive-coated side of said tape, said elevator being adaptable to be used with a deep container having an opening, and a contents-holding bag within said container, said lower length projecting section being attached by means of said obverse adhesive coating to a lower portion of said bag, said overlapping portion extending upwardly from said attachment to said bag, between contiguous areas of said container and said bag, thence outwardly over an edge of said container opening and downwardly over the outer surface of said container, said reverse adhesive coating on said upper length projecting section being removably attached to said container outer surface, whereby the elevation within said container of said bag may be varied.
60. A contents elevator comprising a lower and an upper length of tape each coated on one side with a permanently tacky adhesive and overlapped for a portion of their lengths, adhesive sides in contact, and thereby attached to each other throughout said overlapped portions, a lower length projecting section beyond one end of said overlapping portion presenting an obverse adhesive-coated side of said tape, an upper length projecting section beyond the other end of said overlapping portion presenting a reverse adhesive-coated side of said tape, and a finger hold at the extremity of said upper length projecting section, said elevator being adapted to be used with a deep container having an opening, and a contents-holding bag within said container, said lower length projecting section being attached by means of said obverse adhesive coating to a lower portion of said bag, said overlapping portion extending upwardly from said attachment to said bag, between contiguous areas of said container and said bag, thence outwardly over an edge of said container opening and downwardly over the outer surface of said container, said reverse adhesive coating on said upper length projecting section being removably attached to said container outer surface, whereby the elevation within said container of said bag may be varied.
65. A contents elevator comprising a lower and an upper length of tape each coated on one side with a permanently tacky adhesive and overlapped for a portion of their lengths, adhesive sides in contact, and thereby attached to each other throughout said overlapped portions, a lower length projecting section beyond one end of said overlapping portion presenting an obverse adhesive-coated side of said tape, an upper length projecting section beyond the other end of said overlapping portion presenting a reverse adhesive-coated side of said tape, and a finger hold at the extremity of said upper length projecting section, said elevator being adapted to be used with a deep container having an opening, and a contents-holding bag within said container, said lower length projecting section being attached by means of said obverse adhesive coating to a lower portion of said bag, said overlapping portion extending upwardly from said attachment to said bag, between contiguous areas of said container and said bag, thence outwardly over an edge of said container opening and downwardly over the outer surface of said container, said reverse adhesive coating on said upper length projecting section being removably attached to said container outer surface, whereby the elevation within said container of said bag may be varied.
70. A contents elevator comprising a lower and an upper length of tape each coated on one side with a permanently tacky adhesive and overlapped for a portion of their lengths, adhesive sides in contact, and thereby attached to each other throughout said overlapped portions, a lower length projecting section beyond one end of said overlapping portion presenting an obverse adhesive-coated side of said tape, an upper length projecting section beyond the other end of said overlapping portion presenting a reverse adhesive-coated side of said tape, and a finger hold at the extremity of said upper length projecting section, said elevator being adapted to be used with a deep container having an opening, and a contents-holding bag within said container, said lower length projecting section being attached by means of said obverse adhesive coating to a lower portion of said bag, said overlapping portion extending upwardly from said attachment to said bag, between contiguous areas of said container and said bag, thence outwardly over an edge of said container opening and downwardly over the outer surface of said container, said reverse adhesive coating on said upper length projecting section being removably attached to said container outer surface, whereby the elevation within said container of said bag may be varied.

attachment to said bag, between contiguous areas of said container and said bag, thence outwardly over an edge of said container opening and downwardly over the outer surface of said container, said reverse adhesive coating on said upper length projecting section being removably attached to said container outer surface, and said

5 finger hold serving as a grip to facilitate removal or attachment of said reverse adhesive coating on said container outer surface, whereby the elevation within said container of said bag may be varied.

LLEWELLYN BIGGS.
